Abbott and Nettle of Philadelphia aforesaid

Letters Patent No 9255 Dated January 30 1866

Anti-dated Dec 27 1865

Design for a Cook's Stove

The schedule referred to in these Letters Patent and making part of the same,

shall whom it may concern,

*Be it known that we G. Smith and H. Brown of Philadelphia
County of Philadelphia, State of Pennsylvania, have invented or produced
a new and original design for a cook stove termed the "City" and we do
hereby declare the accompanying Drawing with the following explanation
of the same to form a full, clear and exact description of the said Design.*

For the accompanying drawing

Fig. 1 represents the City cook stove in perspective, and

Fig. 2, is a side view.

*A, is the top plate of the stove, B, the side plate, C, the bottom
plate, D, the front plate, and E, the back plate.*

*The top plate A, is plain, and edged with a plain moulding.
The side plate has plain moulding at the edges, and has also a panel and a
door, and on the edge of each of the same is a plain moulding which incloses
all the ornamental work shown in the drawing.*

*After the door is an ornamental foliated figure, and below
the door is an ornamental panel in which are the words "Abbott
& Nettle Philadelphia".*

2

DES. 2253

At each side edge of the back plate ^P, is a plain moulding, and at the edge of the bottom plate ^P, is an ornamental moulding, a

At each side edge of the front plate ^P, is a plain moulding, and to this plate are hung four doors, the two lower doors having at the edges a plain moulding which encloses the ornamental work, shown in the drawing.

On each of the upper doors is an ornamental framed figure and between the upper and lower doors is an ornamental oblong panel.

We claim the ornamental figures and forms substantially as shown in and by the accompanying drawing, the whole forming an ornamental design for a cook stove.

In testimony whereof we have signed our names to this specification in the presence of two subscribing witnesses.
